UNITED STATES PATENT OFFICE.

GEORGE COLLIS, OF CLINTON, IOWA, ASSIGNOR, BY MESNE ASSIGNMENTS, TO PARAMOUNT HOSIERY FORM DRYING COMPANY, OF CHICAGO, ILLINOIS, A CORPORATION OF ILLINOIS.

ART OF FINISHING AND SHAPING HOSIERY.

1,204,945.

Specification of Letters Patent.

Patented Nov. 14, 1916.

Original application filed June 27, 1911, Serial No. 635,686. Divided and this application filed October 24, 1914. Serial No. 868,439.

To all whom it may concern:

Be it known that I, GEORGE COLLIS, a citizen of the United States, residing at Clinton, in the county of Clinton and State of Iowa, have invented certain new and useful Improvements in the Art of Finishing and Shaping Hosiery, of which the following is a specification, reference being had therein to the accompanying drawing.

10 This invention relates to the art of shaping and finishing hosiery, and has especial reference to a method of treating hosiery-articles consisting in heating, from within, and to a predetermined fabric-drying temperature, a metallic form having its sides relatively narrow in cross-section and converging into substantially-reduced, crease-producing edges; then superposing upon said form a hosiery-article and subjecting 20 the same to the action of heat imparted internally thereto by the form for producing a substantially flattened and creased article.

The present case is a division of an application heretofore filed by me on June 27th, 25 1911, Serial No. 635,686, and patented October 27, 1914, as No. 1,114,966, and wherein is disclosed a novel way of treating hosiery-articles in such manner that, while being dried, they will simultaneously be 30 shaped and creased.

In hosiery mills, the usual method of drying and shaping hosiery, as universally practised prior to my invention, was to stretch a stocking upon a thin, solid wooden 35 board; then several of these were placed upon a rack or similar structure and disposed in a dry-box where they were left sufficiently long to permit drying the stockings. Thereupon, after being withdrawn 40 from the dry-box, the stockings were stripped from the boards and then passed through or subjected to the action of a presser-machine, to shape them. Such shaping was done as a separate step and subsequently to the drying. This method of 45 stretching hosiery upon wooden boards has come to be known, in the art, as "boarding". It is exceedingly slow and expensive, the results are always uncertain because the penetration of the heat may not always penetrate through the fabric so that, as a consequence, the articles are not infrequently withdrawn from the dry-box before they are

completely dry. Moreover, the expense of maintaining a proper degree of heat in the dry-box is great and, even though great care may be exercised, the temperature therein varies considerably. Furthermore, as great quantities of heat escape from the dry-box when it is opened to dispose the stocking-covered boards therein, an intense heat must be maintained therein, always. As a consequence, the fabric of the stocking becomes more or less scorched; the shade thereof, if it be a colored stocking, is somewhat changed; and the strength of the fabric is materially reduced. Then, the rehandling of the articles, after being stripped from the board, to subject them to the action of the presser for shaping and creasing, adds greatly to the expense of manufacture, increases the labor, and materially reduces the output of the mill.

My invention is designed to overcome these objections and disadvantages; the product produced by my method of procedure is greatly superior; and, by a single operation, a hosiery-article, while being dried, is simultaneously shaped in a manner acceptable to the trade. Moreover, by such procedure, I am enabled simultaneously to present heat both to the interior and exterior surfaces of the article, should this be desirable.

In the accompanying drawings, I have shown one form of apparatus for carrying my invention into effect, and which is the form disclosed in my aforementioned case.

In these drawings: Figure 1 is a fragmentary view in sectional elevation of a structure adapted to effect a simultaneous drying, shaping and creasing of a hosiery-article, and by which the article may be subjected to a heating from within as well as from without; Fig. 2 is also a fragmentary view, in sectional elevation, showing a series of metallic, internally-heated shaping members or forms mounted upon a conduit common to several of the members or forms and adapted to supply thereto a heating medium for heating the form from within; and showing also a heat-containing chamber through which the members or forms pass and whereby the hosiery-articles are subjected to an external heating action; and Fig. 3 is a fragmentary view in perspective

of a series of forms, mounted upon a common steam supplying conduit, the particular shape of the members or forms being therein exemplified.

5 Referring to these drawings which, as aforementioned, exemplify a preferred type of structure for carrying my hosiery-treating method into practice, the reference-numeral 1 designates, generally, a base shown, 10 in this instance, as a table or machine-frame. Sustained by the base is a form-supporting member 2 which, in this instance, is illustrated as a circular carrier or conduit. To facilitate rotative movement of the circular carrier, it rests upon rollers 3 carried by the base. The carrier is, in this instance, provided with two channels 4 and 5. Communicating with the channel 4 is a medium-supplying pipe 6^a connecting with a common supply-pipe 6 which, in turn, extends to a suitable source of steam supply. Connecting with the channel 5 is an exhaust pipe 6^b leading to a discharge pipe 6^c. The channel 5 is adapted to receive and convey used steam and water of condensation.

15 Mounted upon the form-supporting member 2, and preferably equidistantly spaced thereon, is a series of hosiery-holding and shaping members or forms 7. Each of the forms is hollow and is formed relatively narrow in cross-section, and the edge thereof is substantially reduced to present a crease producing surface. The sides of the form, as shown, converge into the substantially-reduced edge-portion, just mentioned. 20 By reason of this construction, the article is shaped and creased, the narrowness of the body of the member and the thinness of the edge contributing to this result. Each member or form is provided with a central partition 8 which divides the interior of the form and provides a channel 9 which, 25 through the ports 10 and 11, communicate, respectively, with the channels 4 and 5 in the member-supporting conduit 2.

30 The members or forms are preferably made of a good heat-conducting material. To the end that these forms may be supplied with a heating or drying medium of a predetermined temperature and in predetermined volume, the forms are so mounted upon the member 2 that the ports 10 and 11 of each form shall permit the circulation of the heating medium through the channels of said member 2 and also through each of the forms.

35 The structure which has thus been described in the foregoing, and which is disclosed in detail in my aforementioned application, is adapted to present a heating medium to the interior of each of the forms at a predetermined temperature and in predetermined volume, and whereby each of the forms becomes heated from within so that, when a hosiery-article has been posi-

tioned thereon; the heat of the forms will be imparted to the inside surface of the hosiery-article and effect a rapid evaporation of the moisture in the article. The heat is, thus, applied to the inner surface of the article. 70

The heating medium which is caused to circulate through the member-supporting conduit 2 and through each of the series of forms 7 may be steam, hot air, hot water, or any other appropriate thermal element. 75

80 Where it is found of advantage to subject the hosiery-articles also to an external heating, whereby their outside surface may be dried simultaneously with the application of heat to the internal surface thereof, the following structure may be provided: Supported by the base 1 and in vertical alignment with the member-supporting conduit 2 is a heat-containing chamber 12 formed by a casing wall 13 which encompasses the super-structure of the machine. A top or roof 15 is provided to form, with the wall 13, the aforementioned chamber 12. This chamber is in the path of travel of the upstanding hosiery-drying forms and is adapted to retain heat supplied thereto in any desirable manner and also radiating from the hosiery-forms, from the member 2, etc. While the forms, with the hosiery-articles mounted thereon, are in the chamber 12, the heat contained therein will obviously subject the hosiery-articles to a drying action. 90

95 Upon each of the forms, before it passes into the heat-containing chamber 12, will be placed, by an operator, the hosiery-article to be treated. Usually, as these are brought directly from the dye-room of the mill, they are in a moistened condition. The operator places them upon each form and effects a stretching of the same. The heat which each form imparts to its hosiery-article effects a rapid evaporation of the moisture from the article and, by reason of the described construction of the form, simultaneously effects a shaping thereof. The narrowly-spaced sides and the substantially-sharpened edge of the form produce a finished article which is approximately flat and creased. 105

110 The heat of the form is sufficient, of itself, to dry hosiery-articles and cause the forms to effect the described shaping and creasing thereof. If, however, it be desired to augment the drying action, the forms may be passed into the chamber 12 so that the heat contained therein will effect an external action upon the hosiery-articles and, thus, cause the external surface thereof to be heated. As soon as the hosiery-article is dried and shaped, the operator removes or strips this dried and shaped article from the form. 120

125 The member 2 may be given a rotative movement in any desired manner and by any preferred instrumentality. In Fig. 1, the 130

same is shown as operating under the action of a power-operated drive designated, generally, by the reference-character 14.

From the foregoing, it will be seen that the procedure followed, in treating hosiery-articles under my improved method, is first to effect a heating (from within and to a predetermined drying temperature) of a hollow form, preferably constructed of metal, and having its sides narrow in cross-section and converging into substantially-reduced edge-portions; then manually stretching a hosiery - article longitudinally thereon and retaining the same on the form for the fabric-drying period, during which the fabric of the article is simultaneously dried, shaped, and creased at two oppositely disposed portions; and then removing or stripping the article from the form. The method also contemplates an additional, external heating of the hosiery fabric by positioning the form in the heat-containing chamber 12.

Obviously, the particular aggroupment of instrumentalities herein disclosed as constituting a form of apparatus is not entirely essential in carrying my method into practice except in so far as concerns the hosiery-shaping form, which, to the end that it may simultaneously dry and crease the hosiery-article, should have narrowly-spaced sides which converge to form substantially-reduced edge-portions.

The described successive steps for carrying the method into effect are those which have in practice been found most effective and convenient. The order of the steps may manifestly be changed since the stretching of the hosiery-articles upon the forms may be initially effected, after which the heat-producing medium may be circulated through the form to produce the results already described.

What I claim is:

1. The herein described method of producing a flattened and creased hosiery-article which consists in subjecting the same on its

internal surface to the action of heat and simultaneously forming a single crease only on each of its front and rear edges. 50

2. The herein described method of producing a marketable hosiery-article which consists in passing heat through the article from within the same, subjecting its sides on the internal surface only to a flattening action, and simultaneously therewith subjecting its front and rear portions to a creasing action whereby a single crease only is formed on each of said portions. 55

3. The method of treating a moistened hosiery-article which consists in subjecting the internal surface of its sides to a flattening action and effecting a single crease-like formation at each of its edges whereby the articles will be caused to assume a flattened 60 shape, and simultaneously drying and fixing the fabric of the article by the application of heat to the internal surface thereof so that it will retain its flattened shape. 65

4. The art of finishing hosiery which consists in applying heat to the internal surface of a moistened hosiery-article to evaporate its moisture and at the same time subjecting the same to a flattening and smoothing action on its internal surface whereby the finished article will be substantially flattened 70 75 into one plane at and between its edges.

5. The method of shaping hosiery which consists in stretching the fabric thereof in one direction to the dimensions of the ultimate flattened product, applying heat to the internal surface thereof to evaporate the moisture therefrom and to set the fabric as stretched, and simultaneously ironing the same internally into a form which is flattened at and between its extreme front and rear edges. 80 85

In testimony whereof I affix my signature in presence of two witnesses.

GEORGE COLLIS.
